UNITED STATES PATENT OFFICE

VITA BUCHANAN, OF NEW YORK, N. Y.

BUST-SUPPORTING GARMENT

Application filed June 6, 1929. Serial No. 368,842.

My invention relates to improvements in wearing apparel, and the same has for its object more particularly to provide a simple, convenient and practical woman's combination undergarment.

Further, said invention has for its object to provide an undergarment comprising a nether portion, and a body-portion having incorporated therewith novel bust supporting means.

Further, said invention has for its object to provide an undergarment comprising a nether portion, and a body portion having means for supporting or confining the bust of the wearer, and means for securing said bust supporting or confining means to adjusted position.

Further, said invention has for its object to provide an undergarment comprising an upper or body portion having bust supporting or confining means formed as a part thereof, and nether portion which may be in the form of a skirt or drawers pendant from said upper or body portion.

Further, said invention has for its object to provide an undergarment comprising an upper or body portion having bust supporting or confining means, and a nether portion depending from said body portion provided at its lower edge with stocking supporting means.

Other objects will in part be obvious, and in part be pointed out hereinafter.

To the attainment of the aforesaid objects and ends my invention consists in the novel details of construction, and in the combination, connection and arrangement of parts hereinafter more fully described and then pointed out in the claims.

40 In the accompanying drawings—

Fig. 2 is a corresponding side view;

Fig. 3 is a corresponding rear view;

Fig. 4 is a detail view taken in section along the line 4—4 of Fig. 7;

Fig. 5 is a front view of another embodiment of the invention;

Fig. 6 is a corresponding side view; and

Fig. 7 is a corresponding rear view. The garments to which this invention may be applied are, in general, undergarments or garments for wear close to the body. It should, therefore, be understood that the term undergarment, wherever it appears in the specification and claims, is intended to cover similar garments, such as bathing suits, and should be so interpreted.

According to one embodiment of the invention, an undergarment comprising a body portion and a nether portion, which may be in the form of drawers, is provided with suitable pouches or pockets to receive the breasts of the wearer and these pouches are formed by strips of reinforcement in the general form of a figure 8, there being one loop for each breast. These loops outline the pockets and extend around the sides toward the back of the garment and form bust supporting and confining means.

The loops are supported at their tops or apices close to the front ends of the shoulder straps and preferably to the reinforced parts of the garment to which the front ends of the straps are attached, as by suitable buckles. Under the arms the lines of reinforcement converge gradually to points which are connected across the back of the wearer in any suitable manner as by use of a strap adjustable as to length secured permanently at one end to one of said points under the arms and detachably to the other of said points. Due to such adjustability the bust supporting and confining device may be adjusted to conform closely to the contours of the body. The material of the pouches within the lines of reinforcement may be the same as that of the rest of the garment and in some cases it may be reinforced, as by means of a suitable lining.

Another embodiment of the present invention is in connection with an undergarment including a skirt portion with the body portion.

Referring to Figs. 1, 2 and 3 of the drawings, 10 designates an undergarment having a body portion 11 and a nether portion 12. The body portion may be provided with a strip 13 of reinforcing material at its upper edge and may be suspended from the shoulders of the wearer by shoulder straps 14 having their forward ends preferably detachably secured by suitable means, such as snap fasteners 14a. In the garment illustrated in these figures of the drawings, the nether garment is in the form of drawers and is provided with a crotch closure including members 15 secured in position by lines of stitching 15', and with stocking supporting means including garters 16 at the front and connected at their lower ends with straps 17 extending between the legs of the wearer and connected at their other ends with the rear of the garment at points 18, and garters 19 at the sides connected at their lower ends with straps 20 connected at their other ends with said nether portion at points 20'.

The body portion 11 of the garment has incorporated therewith bust supporting means which include breast receiving pockets or pouches 21 outlined and reinforced at their edges by suitable means such as strips of taping 22 arranged in the general form 25 of a figure 8 of which the loops extend rearwardly at the sides of the garment to points 23. In order to provide a suitable bust supporting or confining effect at the front, the points 23 are connected at the back of the 30 garment by suitable means such as a strap 24, of suitable material, secured at one of said points 23 to the taping and other material, and detachably connected at the other point 23 by means of a fixed clasp member 35 25 and a clasp member 26 adjustable in position on the strap 24. Preferably this strap 24 is arranged at the inside of the material of the body portion as indicated in Fig. 4.

In Figs. 5, 6 and 7 there is illustrated an embodiment of the invention as applied to a garment in which the nether garment is a skirt 28. The bust supporting and confining means may be formed in the same manner as for the garment shown in Figs. 1, 2 and 3 and corresponding parts will be designated by the same reference numerals.

As indicated in both forms illustrated the taping 22 of each of the loops of the figure 8 converges at the top to a point or apex 29 adjacent the front end of the adjacent shoulder strap and is preferably secured to the reinforced portion of the body portion 11 to which the shoulder strap 14 is attached by any suitable means, such as fasteners 30. The taping extends downwardly from these points or apices 29 in such a manner that the breasts are supported largely from these points. The connection between the strips of taping at 31, the joining point of the two loops, maintains the desired transverse spread of the pouches in connection with the strips of taping running from the point 31 along the lower edges of the pouches to the points 23, and from the points 29 to the points 23. Also as a result of the gradual convergence of the strips of taping toward the points 23, the pull on these strips from the rear of the garment is exerted more nearly around the body than up and down.

The garment may be made in knitted, woven or other material, and may be elastic or inelastic as desired. Further the shaping of the body portion at the pouches may be effected in any suitable manner, as for example, by producing a fullness in the material of the body portion by means of the taping or by use of gussets. Furthermore the material of the body portion may be lined or not according to the requirements.

Further, it is to be noted that instead of outlining the pockets or pouches 21 with strips of taping 22, that the said strips, or analogous strips, may be Shirred and sewed along their edges to the body of the garment to form casings to receive strips of elastic 85 webbing which may be secured at their opposite ends to the body of the garment in order to render the pockets or pouches 21 more yielding and thus permit the same to conform more readily to the breasts of the wearer.

It should be understood that various changes may be made in the construction and arrangement of the parts and that various parts may be used without others without departing from the true scope and spirit of the 95 invention.

Having thus described my invention, what I claim and desire to secure by Letters Patent is:
